US00D919987S

(12) **United States Design Patent** (10) Patent No.: **US D919,987 S**
(45) Date of Patent: **** May 25, 2021**

(54) **AIR LOUNGER**

(71) Applicant: **Xiaoou Zhou**, Zhejiang (CN)

(72) Inventor: **Xiaoou Zhou**, Zhejiang (CN)

(73) Assignee: **Wuyi Instinct Outdoor Products Co., Ltd.**, Zhejiang (CN)

(**) Term: **15 Years**

(21) Appl. No.: **29/708,546**

(22) Filed: **Oct. 8, 2019**

(51) LOC (13) Cl. **06-01**

(52) U.S. Cl.

USPC **D6/361**

(58) **Field of Classification Search**
